UNITED STATES PATENT OFFICE.

FREDERICK J. NASH, OF SOMERVILLE, MASSACHUSETTS, ASSIGNOR TO UNITED SHOE MACHINERY COMPANY, OF PATERSON, NEW JERSEY, A CORPORATION OF NEW JERSEY.

SEWING-MACHINE.

1,101,208.

Specification of Letters Patent. Patented June 23, 1914.

Application filed December 7, 1911. Serial No. 664,351.

To all whom it may concern:

Be it known that I, FREDERICK J. NASH, a citizen of the United States, residing at Somerville, in the county of Middlesex and 5 State of Massachusetts, have invented certain new and useful Improvements in Sewing-Machines; and I do hereby declare the following to be a full, clear, and exact description of the invention, such as will enable others skilled in the art to which it 10 appertains to make and use the same.

This invention relates to shoe sewing machines and more particularly to wax thread shoe sewing machines employing a 15 straight hook needle and a shoe supporting horn.

In the manufacture of one class of shoes of the McKay type after the upper is attached to the insole, a welt is presented to 20 the outer or marginal portion of the sole of the shoe and is attached thereto by stitches passing through the welt, upper and insole. In this stitching operation, as performed by the machines heretofore constructed, the 25 work is fed by a feed point which is brought downward into engagement with the welt in advance of the sewing and substantially in a line therewith at intervals and is moved laterally to feed the work, a distance corresponding with the length of the stitch required. The frictional contact of the 30 interior of the shoe with the upper surface of the horn offers considerable resistance to the feeding movement and since the feed point 35 engages the welt at a point some distance in advance of the last stitch formed, the welt is often caused to pucker or bulge between the feed point and the last stitch or is thrust laterally from the desired line especially 40 when the welt is soft and flexible.

The object of the present invention is to produce a wax thread shoe sewing machine of the class having a straight hook needle and a shoe supporting horn by which a welt 45 may be stitched smoothly and evenly to an upper and insole or to any other piece of stock.

With the above object in view the invention contemplates the provision in a shoe 50 sewing machine of the character described of a welt guide and feeding means having spaced work engaging portions arranged to engage the welt and the stock to which the welt is being sewn respectively for positively 55 feeding the same in unison during the sew-

ing operation. By positively feeding both the welt and the stock to which it is sewn during the sewing operation, the welt, and the stock are advanced in a reliable and satisfactory manner and the welt is stitched 60 smoothly and evenly to the said stock.

Further features of the invention consist of certain constructions, arrangements and combinations of parts, the advantages of which will be obvious to one skilled in the 65 art from the following description.

In the drawings illustrating a shoe sewing machine embodying the invention, Figure 1 is a partial front elevation of the machine showing a welt, upper and insole in position on the shoe supporting horn; Fig. 2 is a detail front elevation illustrating particularly the welt guiding and feeding mechanisms; Fig. 3 is a front elevation of a portion of the mechanism shown in Fig. 1 and 75 Fig. 4 is a section taken on the line 4-4 of Fig. 3.

The machine illustrated in the drawing is a wax thread chain stitch straight hook needle machine of the McKay type, in which the shoe is supported upon a rotatable horn during the sewing operation. The construction and arrangement of the straight hook needle 1, the cast-off 2, and the rotary work supporting horn 3, and the mechanism for 80 operating these parts are substantially the same as shown and described in the patent granted to Jacob R. Scott, No. 1,050,568, dated January 14, 1913. The machine illustrated in the drawing is provided with a 85 presser foot indicated at 4 and illustrated particularly in Figs. 2, 3 and 4. This presser foot is provided with a depending portion or foot proper 5 to engage the work and hold the same upon the horn during the 90 stitching operation and with a shank 6 by which it is attached to the usual presser foot supporting block 7. The block 7 is mounted on a presser foot bar 8 which is 95 constructed, arranged and operated substantially as shown and described in said patent. 100

In the drawings the machine has been illustrated as operating to sew a welt to the upper and insole of a McKay shoe. In order to assist in smoothly and evenly attaching the welt to the upper and insole, the machine is provided with a welt guide to 105 guide the welt and to present the same to the insole and upper at the sewing point. This 110 welt guide comprises a rearwardly project-

ing plate 9, carried by and preferably formed integral with the presser foot, said plate having a depending shoulder 10 formed on the rear portion thereof. A plate 11 is attached to the under side of the shoulder 10 on the plate 9 and forms in connection with said plate and the depending work engaging portion 5 of the presser foot a welt guiding passage 12 parallel with the line of feed. A block 13 is attached to the plate 9 between said plate and the lower plate 11 to engage and guide the outer edge of the welt and in order that the welt guide may be adapted to accurately guide welts of different widths, the said block is arranged for adjustment transversely of the line feed. This adjustment is secured in the construction illustrated by forming slots 14 in the plate 9 and securing the block 13 to said plate by screws 15 passing through the slots and screwed into the block.

In order to determine the position of the welt with relation to the upper and insole, an upper gage 16 is formed on the plate 11 to engage the upper in the manner shown particularly in Fig. 2. The plate 11 is secured to the shoulder 10 of the plate 9 by means of a screw 17 passing through a slot 18 in the plate 11 and screwed into said shoulder so that the gage 16 may be adjusted transversely of the line of feed to vary the position in which the welt is presented to the upper and insole. The welt is guided on its way to the guiding passage 12 by a guide bar 19 attached at one extremity to the shank of the presser foot by screws 19^a and at the other to the outer portion of the shoulder 10 by the screw 19^b. The insole and welt are fed at intervals by means of a pair of feed points 20 and 21, mounted on the feed bar 22 and arranged to engage the insole and welt respectively as illustrated particularly in Fig. 2. The feed point 21 is arranged above and in line with the welt guide to engage the outer face of the welt, and the feed point 20 is arranged beyond or to the rear of the welt guide to engage the insole, as clearly shown in Figs. 2 and 4. The feed point 20 is arranged so that its forward extremity projects a sufficient distance in advance of the point 21 to bring the said point 20 into engagement with the insole at substantially the same time that the feed point 21 engages the welt. A member 23 mounted on the presser foot supporting block 7 and the portion 5 of the presser foot are respectively provided with grooves for guiding the feed points 21 and 20 in their movements toward and from the work. The construction and arrangement of feed bar 22 and the mechanism for operating said bar are substantially the same as illustrated and described in the patent referred to above. When the feed points are brought forward into respective engagement with

the insole and welt and are moved laterally by the operation of said mechanism, the welt and the insole with the upper attached thereto are advanced in unison a distance corresponding to the length of the stitch in a certain and reliable manner. By the simultaneous positive feed of the shoe and the welt, the operator is enabled to stitch the welt smoothly and evenly to the upper and insole without the formation of folds or wrinkles in the welt and without lateral displacement of the welt regardless of how thin or flexible the welt may be.

Although the machine embodying the present invention as illustrated and described is of particular utility in the operation of attaching a welt to an assembled upper and insole, its use is not limited to such an operation but the machine may be conveniently employed in other analogous operations such as the sewing of a welt to an outsole.

Having explained the nature and object of the invention and having specifically described one form of mechanism in which it may be embodied, what is claimed is,—

1. A wax thread shoe sewing machine, having, in combination, stitch forming mechanism including a straight hook needle, a shoe supporting horn, a welt guide, and work feeding mechanism having spaced work engaging portions arranged respectively beyond the welt guide and in line with the welt guide to engage the stock to which the welt is being sewn and the welt.

2. A wax thread shoe sewing machine, having, in combination, stitch forming mechanism including a straight hook needle, a shoe supporting horn, a welt guide, a feed point arranged in line with the welt guide to engage the welt, a second feed point arranged beyond the welt guide to engage the stock to which the welt is being sewn, and means to operate said feed points to feed the said stock and the welt in unison.

3. A wax thread shoe sewing machine, having, in combination, stitch forming mechanism including a straight hook needle, a shoe supporting horn, a presser foot, a welt guide mounted on the presser foot, a feed bar, a feed point mounted on said bar and arranged in line with the welt guide to engage the welt, a second feed point mounted on said bar and arranged beyond the welt guide to engage the stock to which the welt is being sewn, and means to operate said bar to cause the feed points to engage and feed the welt and said stock in unison.

4. A wax thread shoe sewing machine having, in combination, stitch forming mechanism including a straight hook needle, a shoe supporting horn, a presser foot, a welt guide mounted on the presser foot and having provision for adjustment to guide welts of different widths, an upper gage

mounted on the presser foot and arranged for adjustment to vary the position of presentation of the welt to the upper and insole, a feed bar, a pair of feed points mounted on said feed bar, and arranged respectively in line with the welt guide and beyond the welt guide to engage the welt and insole respectively and means to operate said feed points to feed the insole and welt

10 in unison.

5. A wax thread shoe sewing machine having, in combination, stitch forming

mechanism including a straight hook needle, a shoe supporting horn, a welt guide, a feed point arranged to engage the welt, a second feed point projecting in advance of said first feed point to engage the stock beneath the welt and means to operate said feed points to feed the said stock and the welt in unison.
